UNITED STATES PATENT OFFICE.

HELEN C. ANDERSON, OF PENSACOLA, FLORIDA.

DESIGN FOR AN IMAGE.

41,802.

Specification for Design.

Patented Sept. 26, 1911.

Application filed April 4, 1911. Serial No. 618,940. Term of patent 7 years.

To all whom it may concern:

Be it known that I, HELEN C. ANDERSON, a citizen of the United States, residing in Pensacola, in the county of Escambia and State of Florida, have invented a new, original, and ornamental Design for an Image, of which the following is a specification, reference being had to the accompanying drawing, forming part thereof.

The figure is a perspective view of an image showing my design.

I claim:

The ornamental design for an image as shown.

HELEN C. ANDERSON.

Witnesses:

ARTHUR A. BROWN,
E. D. ANDERSON.
